UNITED STATES PATENT OFFICE.

MAX W. GOLDBERG, OF PORT WASHINGTON, WISCONSIN, ASSIGNOR TO MODERN POURING DEVICE CO., OF PORT WASHINGTON, WISCONSIN, A CORPORATION OF WISCONSIN.

POURING AND LIFTING DEVICE.

Application filed September 7, 1926. Serial No. 133,986.

My invention has relation to improvements in pouring and lifting devices of that type wherein the apparatus is moved along a rail so as to convey a load from one point to another.

The primary object of the invention is to provide a construction not only adaptable for raising the ladle and for conveying the said ladle containing molten metal from a point where the ladle is filled, to a point of discharge, but furthermore adapted to provide for the ready removal of the ladle and the attachment of the apparatus to a load to be lifted and transported, such as castings, molds and the like, the construction being such that the lifting operation is accomplished quickly and easily, and the lifting capacity and the carrying capacity greatly increased, only one man being necessary in the successful operation of the device, and being able to accomplish more work in a given time than has heretofore been possible by several operators.

The invention also has as an improved object, the provision of means whereby the load may be lowered instantaneously or slowly as desired.

The invention furthermore contemplates extreme accuracy of control, which is so essential in apparatuses of this character.

With the above primary objects, and other incidental objects in view, the invention consists of the device and parts, or the equivalents thereof as hereinafter more fully pointed out.

In the accompanying drawings,

Fig. 1 is an elevation of the complete device for use in connection with a ladle for transporting and pouring molten metal and other loads;

Fig. 2 is a fragmentary elevation of the opposite side of the apparatus to that shown in Figure 1;

Fig. 3 is a fragmentary elevation at right angles to Fig. 2;

Fig. 4 is a longitudinal sectional view on the line 4-4 of Fig. 1; and

Fig. 5 is a vertical sectional view on the line 5-5 of Fig. 4.

Referring to the drawings, the numeral 6 indicates a bail, the extremities of the

side arms thereof being formed into bearings 7-7.

Connected to the horizontal arm of the bail, and extending upwardly therefrom, is a yoke 8.

The numeral 9 indicates a vertical rack bar. The lower untoothed portion of this bar extends freely through an opening in a portion 10 of the casting, and from below the casting, the rack bar is circular in cross section, and passes through an opening in the horizontal member of the yoke 8. The lower extremity of this rounded portion of the rack bar is threaded to receive a nut 11, a washer 12 being interposed between the upper side of said nut and the underside of the horizontal member of the yoke. By this arrangement, the yoke may be circularly adjusted upon the rounded extremity of the rack bar, simply by loosening the nut, when the desired adjustment is obtained, the nut of course is again tightened. When the yoke, through said adjustment, is turned, of course, the bail 6, and the load carried thereby are turned therewith.

The upper end of the rack bar carries a roller 13 which is adapted to ride along vertical guide bars 14-14, said guide bars extending upwardly from the framework. The numeral 15 indicates a horizontal shaft, mounted in the bearing portions 16 and 17 of the frame 10.

Fast on the shaft 15, and preferably keyed thereto, is a ratchet wheel 18. A sleeve 16' which is free to turn on the shaft 15, has formed integrally therewith, an extension 19. The upper end of this extension has rigidly connected thereto, a bent handle 20.

Also extending downwardly into the extension is a recess 21, into which passes a rod 22, the lower end of said rod being in the form of a pawl 23 which normally engages the teeth of the ratchet wheel 18, and is held in normal engagement with said teeth by means of a coiled spring 24 surrounding the rod 22, and having its lower end bearing against the pawl, and its upper end bearing against a sleeve 25 fitted in the upper end of the recess 21, said sleeve loosely surrounding the rod 22.

Extending upwardly from the extension

19 is a standard 26, to the upper end of which is pivoted a bell-crank lever 27. To one arm of this bell-crank lever is pivoted a link 28, the outer end of said link being pivoted to a finger piece 29, which finger piece in turn is pivoted to the bent handle 20. The other arm of the bell-crank lever is pivoted to the rod 22.

The rod 22 carries turnably thereon between two nuts 30—30, a stop finger 31, provided on its underside with a recess 32. If it be assumed that the handle 29 has been depressed so as to raise the pawl 23 out of engagement with the teeth of the wheel 18, the stop finger 31 is turned to the position shown in Fig. 1, and in such position, the recess 32 of said stop finger is brought into engagement with a pin 33 extending laterally from an arm 34 of the framework.

In this manner, the pawl is maintained temporarily out of engagement with the ratchet wheel 18, when desired.

Mounted fast on the shaft 15 at an intermediate point thereof is a toothed wheel 35 which is so positioned as to engage with the teeth of the rack bar 9.

Also mounted fast on the shaft 15 is a ratchet wheel 36. A sleeve 17' loose on the shaft 15 has formed integrally therewith a brake drum 37. Extending laterally inwardly from the side of this drum are pins 38, preferably three in number, and upon each of these pins is mounted a spring-pressed pawl 39. The periphery of the brake drum is a spaced from and surrounds the ratchet wheel 36, and the pawls 39. A brake band 40 is passed around the periphery of the brake drum. A plate 41 riveted to one end of this brake band, is provided with a reduced tongue 42, which is looped around a pin 43 extending laterally from and preferably integral with the casting. The opposite end of the brake band has also connected thereto, a plate 44, which is formed with a projecting tongue 45, circular in cross section. This tongue passes through an opening in an arm 46, pivotally mounted upon and extending upwardly from the pin 43.

The tongue 45 on each side of arm 46, carries nuts 47 and washers 48, whereby the tongue is prevented from pulling out of the opening of the arm 46. The upper end of the arm 46 is slotted, and a lever 49 passes through the slot and fulcrums on the lower edge of said slot. One end of this lever is preferably bent upwardly at an incline to form a handle portion, and the other end of the lever carries a weight, 50.

Back of the lower portion of the rack bar, the frame is provided with a vertical slot 51, the side arms formed by the slot having cross pins 52—52 mounted therein, and on these cross pins, between the arms, are mounted rollers 53—53, which engage the untoothed edge of the rack bar, and serve as

anti-friction guides for the rack bar in its vertical movement.

Figure 1 of the drawing shows the apparatus used in connection with a ladle 54, adapted to contain molten metal. The ladle is supported in a hoop or ring 55, and this hoop has extending therefrom, trunnions 56—56, said trunnions being supported in the looped ends of the side arms of the bail 6. One of these trunnions is extended outwardly beyond the bearing, and is then bent upwardly at an angle to form a handle 57. When this handle is turned, it is obvious that the ladle is tilted to a position to discharge its contents.

A cross pin 59 is mounted in the upper ends of the vertical guide bars 14, and connected to this pin is a hook 59, upon which the entire device is adapted to swivel.

The parts or elements which go to make up the brake mechanism have already been described. The operation of this brake mechanism is as follows: The weight 50 on the lever 49 normally holds the parts in such position that the brake band is tightly engaging the periphery of the brake drum, in order to hold said brake drum against the rotation. When it is desired to decrease the extent of the frictional contact of the brake band with the periphery of the brake drum, the bent end of the lever 49 is depressed by hand against the contrary force exerted by the weight 50. The depression of said lever will cause a turning of the arm 46 on the pin 43 in a direction to loosen the brake band, and thereby relieve the frictional contact of said band, and the extent of the relieving of the frictional contact is of course readily regulated by the extent to which the lever 49 is depressed. When pressure on the lever 49 is removed, the brake band is automatically brought into effective braking operation by reason of the weight 50 turning the lever 49 back to its normal position, and in which position, the brake band is pulled into firm engagement with the periphery of the brake drum.

In the use of the apparatus, the hook 59 is engaging a carriage (not shown) adapted to travel along an upper head support or track (also not shown). If the apparatus is to be used for conveying a ladle containing molten metal, the said ladle connected to the bail 6 in the manner hereinbefore described. The carriage from which the apparatus is suspended is then caused to travel along the track to a point where the ladle is to be filled with the molten metal. After the filling operation, the apparatus is then caused to travel to a point convenient for filling the molds. In view of the fact that the device is swiveled on the hook 59, it is obvious that said device can be turned and the ladle thereby properly positioned for discharge into any desired mold.

If it is desired to vary the weight of the ladle for pouring the metal into molds of different heights, the rack bar 9 is operated to either raise or lower the same. It will be noticed that in Fig. 1, the rack bar is shown as raised to the limit of its upward movement.

If, now, it is desired to lower the ladle, the finger 29 is depressed and this has the effect through the bell crank lever 27, of raising the rod 22, which, of course, lifts the attached pawl 23 out of engagement with the teeth of the wheel 18. The pawl 23, having been raised out of engagement with the teeth of the wheel 18, and the brake band having been released, the weight of the load will cause a descent of the rack bar, and a consequent rotation of the shaft 15 by reason of the engagement of the teeth of the rack bar with the tooth wheel 35. Of course, the ratchet wheel 36 is also rotated with the shaft, and the direction of rotation is counter-clockwise as indicated by the arrow Figure 5. In view of the fact that the brake band has been adjusted to a non-braking position, the brake drum 37 is also rotated with the ratchet wheel 36, by reason of the locking engagement effected by the pawls, 39.

After the ladle has been lowered, as described, and it is desired to again raise the said ladle, the lever 20 is operated in a reverse direction, or in other words turned downwardly, and this has the effect of turning the sleeve 16' in a direction to cause the pawl 23 to act on a tooth of the wheel 18 and partially rotate said wheel and the shaft 15. At the same time, of course, the toothed wheel 35 and the ratchet wheel 36 are also rotated. The direction of rotation in this instance is clockwise, and hence the ratchet wheel 36 will slip by the pawls 39, which are held in a relatively fixed position by the brake drum, the brake band having been previously tightly adjusted around the periphery of the brake drum.

The next successive movement is the raising of the lever 20. This will cause a turning of the member 19 in a direction to permit the pawl 23 to ride over the teeth of the wheel 18, without imparting rotation to said wheel, and necessarily without rotation to the shaft 15. On this up movement of the lever 20, the shaft is held against rotation in a direction to permit of the descent of the load by reason of the engagement of the pawls 39 with the teeth of the toothed wheel 36, the brake drum itself being held stationary by the tight adjustment of the brake band 40.

It will be noticed that each pawl 39 is held yieldingly in engaging position by spring pressure, the spring for each pawl being indicated by the numeral 60.

Whenever it is desired to maintain the pawl 23 out of engagement with the teeth

of the wheel 18, the stop finger 31 is swung to a position where its recess engages the pin 33. Of course, after this adjustment, and when it is desired to again permit the pawl 23 to engage the teeth of the ratchet wheel 18, all that is necessary to be done is to swing the stop finger 31 in a reverse direction so as to bring its recess out of engagement with the pin 33.

From the foregoing description, it will be seen that I provide a positively operating device which is adapted to be raised and lowered and transported from one point to another, the operation being accomplished quickly and easily.

Also by the particular construction described, the lifting and carrying capacity of the apparatus is greatly increased, and the service of only one man is necessary in carrying out the successful operation of the device, and this one man in the handling of the apparatus, is able to accomplish more work in a given time, than has heretofore been possible even where several operators were employed.

If it is desired to use the apparatus for transporting castings, molds and the like, it takes but a half minute to remove the ladle and its ring and the trunnions and to attach the bail 6, to the other articles to be transported. For instance, it can be used for the purpose of shaking out any reasonable size mold by placing a bar in the loops of the bail 6, and suspending from said bar a device which will engage the mold. The apparatus can then be transported to the desired point, and then caused to move repeatedly upwardly and downwardly so as to shake out the mold.

What I claim as my invention is:

1. In a pouring and lifting device, the combination of load carrying mechanism, a rack bar to which the load carrying mechanism is connected, a shaft, a ratchet wheel mounted fast on the shaft, a toothed wheel also mounted fast on the shaft and engaging the rack bar, another ratchet wheel mounted fast on the shaft, sleeves loosely surrounding the shaft, one of said sleeves formed with an extension provided with a recess, and the other of said sleeves formed with a brake drum, a spring-actuated rod extending into the recess of the extension of the first referred to sleeve, the inner end of said rod provided with a pawl normally engaging the teeth of the ratchet wheel with which it cooperates, a finger turnably mounted, but non vertically movable on the rod, a pin with which said finger is adapted to be swung into engagement whereby the pawl is held out of engagement with this ratchet wheel, a spring-pressed pawl extending laterally from the side of the brake drum and engaging the ratchet wheel with which it cooperates, the periphery of the brake drum sur-

- rounding this ratchet wheel and the pawl, an upright arm, a pin upon which said upright arm is movably mounted, a weighted lever fulcrumed on the upright arm, and a 5 brake band surrounding the periphery of the brake drum and having one end fast, and its opposite end secured to the upright arm.
2. In a pouring and lifting device, the combination of load carrying mechanism, a 10 rack bar connected to the load carrying mechanism, a shaft, a toothed wheel fast on the shaft and engaging the rack bar, means for rotating the shaft in a direction to cause the toothed wheel to raise the rack bar and 15 thereby lift the load carrying mechanism, and to permit of the rotation of the shaft in the opposite direction to allow for the descent by gravity, of the rack bar and its load, a ratchet wheel mounted fast on the 20 shaft, a brake drum mounted loosely on the shaft, a pawl pivoted to the brake drum and engaging the teeth of the ratchet wheel, a 25 brake band surrounding the brake drum, and means for controlling the degree of engagement of the brake band with the brake drum, whereby upon the release of the brake band and the descent of the load by gravity, the 30 loose brake drum will rotate with the ratchet wheel through engagement of the pawl with 35 the ratchet wheel, and whereby, when the shaft is turned in the opposite direction to effect the lifting of the rack bar through the engagement of the toothed wheel with said rack bar, and when the brake band is set, the ratchet wheel will slip by the pawl, the 40 latter being held in a relatively fixed position, the load carrying mechanism, however, when the shaft is not under rotation, being held against retrograde reverse movement by the engagement of the pawl with the ratchet wheel.
3. A metal pouring device, comprising a 45 portable frame, a vertically movable member carried thereby and having means for holding a container, means for positively elevating the movable member with respect to the frame, and brake means for holding the movable member in adjusted position and for controlling the lowering of the movable member by gravity.
4. A metal pouring device, comprising a 50 portable frame, a vertically movable member carried thereby and having means for holding a container, means for positively elevating the movable member with respect 55 to the frame, and a brake drum and brake

band means for holding the movable member in adjusted position, and for controlling the lowering of the movable member.

5. A metal pouring device, comprising a 60 portable frame, a vertically movable member carried thereby and having means for holding a container, means for positively elevating the movable member with respect to the frame, a brake drum and brake band 65 means for holding the movable member in adjusted position and for controlling the lowering of the movable member, and a counterbalanced lever normally holding said brake band in braking position, and causing 70 the release of said brake band when the lever is operated.

6. A metal pouring device, comprising a 75 portable frame having upstanding guide bars, a rack bar interposed between and guided by said bars, and having means for holding a container at its lower end, a shaft journaled in the frame, a gear wheel mounted fast on the shaft and in mesh with the teeth of the rack bar, a brake drum surrounding the shaft and having a pawl and ratchet wheel engagement with the shaft, a 80 brake band surrounding said brake drum, and means for operating said brake band.

7. A metal pouring device, comprising a 85 portable frame having upstanding guide bars, a rack bar interposed between and guided by said bars, and having means for holding a container at its lower end, a shaft journaled in the frame, a gear wheel mounted fast on the shaft and in mesh with the teeth of the rack bar, a brake drum surrounding the shaft and having a pawl and ratchet wheel engagement with the shaft, a 90 brake band surrounding said brake drum, and a counterbalanced lever connected to said brake band to normally hold the brake band 95 in braking position, and to cause the release of said brake band when the lever is operated.

8. A metal pouring device, comprising a 100 portable frame, a member carried by said frame and movable longitudinally therewith and having means for holding a container, means for elevating the movable member with respect to the frame, and brake means for holding the movable member in adjusted position and for controlling the lowering of the movable member by gravity.

In testimony whereof, I affix my signature.

MAX W. GOLDBERG.
